UNITED STATES PATENT OFFICE

2,195,106

BRACELET

Charles A. Domler, Providence, R. I., assignor
to The Hadley Company, Inc., Providence,
R. I., a corporation of Rhode Island

Application July 13, 1939, Serial No. 284,290

5 Claims. (Cl. 24—71)

This invention relates to bracelets of the type having an extensible connector, and its principal object is to provide a bracelet which is of unique design and of pleasing appearance, which is of strong and durable construction and which may be readily manipulated either to permit removal or to vary its effective length.

Further objects relate to various features of construction and will be apparent from a consideration of the following description and accompanying drawing, wherein:

Fig. 1 is a top plan view of a bracelet constructed in accordance with the present invention;

15 Figs. 2 and 3 are top plan views of modified forms of the invention;

Fig. 4 is a side elevation of the extensible connector;

Fig. 5 is a top plan view of the connector when 20 in extended position;

Fig. 6 is an enlarged longitudinal section through the connector shown in Fig. 4; and

Fig. 7 is an enlarged section on the line 7—7 of Fig. 4.

25 Referring to Figs. 1 and 4 to 7, inclusive, the particular embodiment shown therein comprises a bracelet chain having a plurality of links 1 which may be of any appropriate design or configuration here shown for the purpose of illustration as being generally pear-shaped. The links are pivotally interconnected with each other by clips 3 which may be of conventional design and construction and between two of the links is an extensible connector designated by the numeral 5.

The particular connector 5 here shown comprises an elongate base member or section 10 which is generally U-shaped in cross section, having centrally disposed upstanding ears 11 (Figs. 1, 4 and 5). One end of the section is shaped to provide a socket 12 by means of which the section may be pivotally connected to one of the bracelet links, and the opposite end of the section is formed with a resilient tongue 14 30 which is bent inwardly so as to form a socket 15, the free end of the tongue being tapered and projecting upwardly at a slight angle to provide a pawl, as shown in Figs. 5 and 6.

45 The socket 15 pivotally connects the section 50 12 with one end of an intermediate loop-like member or link 18, constituting one of a plurality of folding members and having a design of substantially the same motif as the design of the links 1 and the opposite end of the link 55 18 is received in a socket 19 from one end of an

other folding member or section 20. The lateral edges of the member 20 are formed with depending walls 20 which terminate in inwardly directed flanges 22 and between their ends the walls 21 are formed with slots adapted to receive the beaded ends of the ears 11, as shown in Fig. 7. Adjacent to its free end, the section 20 is formed with a stop bar 25 (Fig. 6) extending from one flange to the other.

An extensible member or section 30 is slidably 10 mounted between the walls 21 and flanges 22 of the section 20 and its under surface is formed with a series of ratchet teeth 31 engageable with the pawl 14 when the parts are in folded position, as shown in Fig. 7. The inner end of the 15 section 30 is formed with a depending lug 32 engageable with the stop bar 25 to limit the outward sliding movement of the section and its outer end is formed with a socket 34 by means of which the connector is pivotally secured to one 20 of the links of the bracelet.

The construction and arrangement of parts is such that the sections 10, 18 and 20 may be folded together so that the section 20 is received substantially within the confines of the section 10, 25 with the lateral portions of the links 18 extending about and providing, in effect, a guard for the folded parts, as shown in Figs. 1 and 4. When thus folded the ears 14 releasably hold the sections 10 and 20 in folded relation and as the lateral portions of the links 18 extend outwardly in spaced relation to the sides of the sections 10 and 20, they also provide a readily accessible 30 grip by means of which the parts may be conveniently unfolded. When the parts are in folded 35 position (Figs. 4 and 7), the pawl 14 and ratchet teeth 41 are brought into operative relation and when the parts are unfolded the pawl and ratchet teeth are disengaged, thus permitting the same series of adjustments as are possible with any of the various types of extension attachments constructed in accordance with the invention set forth in my prior Patent No. 1,966,063.

It will be noted that the link 18 not only provides an essential part of the device, possessing the aforementioned utilitarian features, but because of its design or configuration greatly enhances the ornamental appearance of the bracelet. As above pointed out, the design of the link 50 18 may be varied in accordance with the design or configuration of the bracelet links 1 and as illustrative of such variations reference is made to the modification shown in Figs. 2 and 3. In Fig. 2 the links 1* are hexagonal-shaped and the 55

link 18^a of the connector 5^a is likewise hexagonal shaped thus presenting a design or configuration having substantially the same motif as that of the links 1^a; whereas in Fig. 3 the link 18^b of the connector 5^b, although presenting a design of substantially different shape than that of the links 18 and 18^a, nevertheless possesses the same motif as the links 1^b. Other than the design of the links 1^a, 1^b, 18^a and 18^b the parts are substantially identical to those of the previously described embodiment and the same reference characters are applied thereto.

While I have shown and described different embodiments of the invention, it is to be understood that this disclosure is for the purpose of illustration and that various changes in shape, proportion and arrangement of parts, as well as the substitution of equivalent elements for those herein shown and described, may be made without departing from the spirit and scope of the invention as set forth in the appended claims.

I claim:

1. In a bracelet having a plurality of interconnected links, an extensible connector comprising a plurality of folding members, one of said members being in the form of an elongate loop-like link having its elongate side portions extending in spaced relation about the other member when in folded position and providing a grip by means of which the links may be swung to unfolded position, and means carried by one member and arranged to project through the opening in said loop-like link so as to engage and releasably hold another of the members in folded position.
2. In a bracelet having a plurality of interconnected links of substantially the same size and design, an extensible connector comprising a plurality of folding members, one of said members being in the form of an elongate loop-like link having a design of substantially the same motif as the design of said links, the elongate side portions of said link extending about the other members when in folded relation therewith and providing a grip by means of which the links may be swung to unfolded position, and means carried by one member and arranged to project

through the opening in said loop-like link so as to engage and releasably hold another of the members in folded position.

3. In a bracelet having a plurality of interconnected links, an extensible connector comprising two sliding members connected to slide endwise, and a folding member hinged to one of said sliding members, said folding member being in the form of an elongate loop-like link having its elongate side portions disposed about the other members when in folded position and providing a grip by means of which the links may be swung to unfolded position, and means carried by one member and arranged to project through the opening in said loop-like link so as to engage and releasably hold another of the members in folded position.

4. In a bracelet having a plurality of interconnected links of substantially the same size and design, an extensible connector comprising two sliding members connected to slide endwise, and a folding member hinged to one of said members, said folding member being in the form of an elongate loop-like link having a design of substantially the same motif as the design of said links, said link extending about said members when in folded relation therewith and providing a grip by means of which the links may be swung to unfolded position, and means carried by one member and arranged to project through the opening in said loop-like link so as to engage and releasably hold another of the members in folded position.

5. An extensible connector comprising three relatively foldable members, the intermediate member being in the form of an elongate loop-like link extending about the other two members when in folded position, and releasable holding means carried by the foldable link on one side of the intermediate link and arranged to project through the opening in said intermediate link so as to engage the foldable link on the other side of the intermediate member, thereby releasably to hold the links together when in folded relation.

CHARLES A. DOMLER.
